(57) CLAIM

The ornamental design for a pet toy, as shown and described.

DESCRIPTION

FIG. 1 is a top perspective view of the pet toy.

FIG. 2 is a front elevation view of the pet toy.

FIG. 3 is a back elevation view of the pet toy.

FIG. 4 is a left side elevation view of the pet toy.

FIG. 5 is a right side elevation view of the pet toy.

FIG. 6 is a top plan view of the pet toy; and,

FIG. 7 is a bottom plan view of the pet toy.

The term "Starmark" and paw print design shown on the pet toy in dashed lines are registered trademarks of Starmark Pet Products, Inc. and form no part of the claimed design.
